SWING

James W. Miller, Roosevelt, Okla.

Application August 4, 1938, Serial No. 223,120

8 Claims. (Cl. 155—58)

This invention relates to an improved swing having a chair-shaped seat adapted to be formed from a pneumatic tire casing.

It is an aim of this invention to provide an improved chair-shaped seat for swings which will be shaped to provide the utmost comfort and safety, and the exposed portion of which will be sufficiently flexible and resilient to prevent injury to furniture or other elements against which the swing may accidentally come in contact while in use.

More particularly, it is an object of this invention to provide an improved chair-shaped swing seat which may be economically manufactured from worn out or abandoned tire casings to form a durable and comfortable structure.

Other objects and advantages of the invention will hereinafter become more fully apparent from the following description of the drawing, which illustrates a preferred embodiment of the invention, and wherein:

Figure 1 is a front elevational view thereof.

Figure 2 is a fragmentary side elevational view of the same.

Figure 3 is a longitudinal vertical sectional view taken on the line 3—3 of Figure 1, and

Figure 4 is a transverse horizontal sectional view taken on the line 4—4 of Figure 1.

Referring more particularly to the drawing, wherein like reference characters designate like or corresponding parts throughout the different views, 10 designates generally the seat of the swing and 11 the resilient supporting means therefor.

35 The seat 10, which is chair-shaped, is formed from a pneumatic tire casing, a portion of the tread and side walls of which is cut off and discarded to leave the remaining portion including the circular bead, which remains intact there-
40 with. The portion of the tread and side walls from which the seat 10 is formed, which is designated 12, is positioned so that the tread side 13 will be uppermost and the intermediate portion and one end of the member 12 is turned inside out to form the concave seat 14, and the rounded curved back 15. The opposite end 16 which is left in its normal shape, forms a rounded hump as best seen in Figures 1 and 3 to provide a leg rest.

50 The upper end of the back 15 is adapted to be widened by splitting the center portion thereof, from the top, and pulling the opposite sides outwardly, to form a V-shaped notch 17 which is covered by the V-shaped strip 18, cut from the 55 unused portion of the tire casing and secured

to the inner side of the back 15 by the fastenings 19.

As best seen in Figures 1 and 2 the beads 20 which are left integral with the portion 12 are cut away from the upper portion of the back 5 15, as indicated at 21, and are bent through an arc to form the arcuately shaped arms 22 which extend below the leg rest 16 and which are twisted at 23 and curved upwardly to connect with the end of the portion 12 which forms leg rest 16. 10 Between the twist 23 and the point at which the beads connect with the leg rest end 16, is formed the loops 24, for a purpose which will be herein-
after described.

In order to retain portion 12 in the form of a 15 seat 14, back rest 15 and leg rest 16, the trans-
verse rigid straps 25 and 26 are provided which are shaped to correspond to the outer side of the back 15 and leg rest 16 respectively. Strap 25 is secured to the back 15 by the fastenings 19 and 20 to the V-shaped member 18 by the fastening 27, and the opposite ends of the strap 25 are bent to form the hooks 28 which engage the beads 20 to assist in supporting them adjacent their upper end. The strap 26 is secured to the under side 25 of the foot rest by the fastening 29 and to the beads 20 adjacent the twisted point 23 by similar fastenings 29, to retain the shap of the leg rest 16 and the relative position of the adjacent portion of the beads 20 thereto.

30 Secured to the under side of the seat 14 are the corresponding ends 30 of the supporting straps 31, which form a part of the supporting means 11, and which extend upwardly and are looped at their opposite ends to connect with the rings 32. Straps 31, intermediate of their ends, are secured to the intermediate portion of the arms 22 and combine with the rigid straps 25 and 26 to retain the beads 20 in their proper relative position to the remaining parts of the seat 10. 40

A crossbar 33 is provided, adjacent the opposite ends of which are secured the depending chains 34, having the snap hooks 35 connected to their free ends and adapted to removably engage the rings 32 for supporting the chair 10 from the 45 bar 33. Bar 33, in turn, is supported by the diverging chains 36 which are connected at their lower diverging ends to the bar 33 and at their upper ends to the chain 37.

An expansion coil spring 38 has the intermediate portion of a pair of metal strips 39 threaded therethrough from opposite directions, with the opposite ends of each of said strips bent outwardly upon themselves to form the hooks 40 which engage around the opposite ends of the spring 38 50 55

- to connect the strips thereto with the intermediate portions thereof projecting in opposite directions therefrom. The intermediate portion which projects through the lower end of the 5 spring 38 is connected by means of the hook 41 to the upper end of the chain 31, while the corresponding portion of the other strip 39 which projects upwardly from the spring 38 is connected to a hook 42 secured in a ceiling, or other 10 suitable elevated support as indicated at 43, for resiliently supporting the swing.

From the foregoing it will be seen, that a downward pull on the seat 10 will contract the spring 38 to thereby form a spring support. The occupant of the swing sits in the seat portion 14 and leans back against the back rest 15 with his or her legs dangling over the leg rest 16, or if desired, the feet may be moved outwardly and into engagement with the loops 24 which will then be 20 employed as stirrups for supporting the feet. Straps 31 and the arms 22 will prevent the occupant of the swing from falling out on either side thereof, and the rigid members 25 and 26 will retain the shape of the chair-shaped seat 10 in 25 the form as illustrated.

The supporting straps 31, although forming a part of the supporting means 11 of the chair 10, are permanently secured to the chair by means of the fastenings 44 which connect straps 31 to the 30 arms 22 and to the seat 14, so that when the swing is disassembled the rings 32 will be disconnected from the hooks 35 leaving the straps 31 as a part of the chair 10.

Various modifications and changes in the construction of the swing may obviously be made and are contemplated, as only a preferred embodiment of the invention has been illustrated and described, and the right is therefore expressly reserved to make such variations and changes as 40 do not depart from the spirit and scope of the invention as hereinafter defined by the appended claims.

I claim as my invention:

1. A device of the class described comprising a 45 flexible strip, the intermediate portion and one end thereof being bent lengthwise and transversely to form a concave seat and rounded back, respectively, strips connecting the opposite sides and opposite ends of said first mentioned flexible strip, said last mentioned strips being positioned above and at opposite sides of said first mentioned flexible strip to form sides, and means connecting said seat portion and said sides and extending upwardly therefrom to suspend the 50 device.

2. A device as in claim 1, and rigid straps extending transversely of the opposite ends of said flexible strip and shaped to correspond thereto, said straps being secured to said opposite ends to 55 retain said flexible strip in its proper shape.

3. A swing comprising a section of a pneumatic tire casing, said section having its intermediate portion and one end turned inside out and bent

lengthwise and crosswise to form a concave seat and a rounded back, respectively, the opposite end of said section being bent lengthwise and crosswise in the opposite direction to form a leg rest, strips connecting the ends of corresponding sides 5 of said section, the intermediate portions of said strips being arcuately shaped and disposed above the sides of the seat to form arms, reinforcing means disposed transversely of the opposite ends of said section to retain its shape, and means connected to said seat portion and to the arms and extending upwardly therefrom for suspending the device. 10

4. In a swing, a chair-shaped member, and resilient suspending means connected thereto and adapted to be suspended from a ceiling or the like; said chair-shaped member being formed from a portion of a pneumatic tire casing having its intermediate portion and one end turned inside out and bent lengthwise and crosswise to 20 form a concave seat and rounded upwardly extending back, respectively, the opposite end being bent lengthwise and crosswise in the opposite direction and turned downwardly to form a leg rest, and rigid reinforcing members secured across 25 the ends of said portion.

5. A swing having a chair-shaped seat formed from a section of a pneumatic tire, one end and the intermediate portion of said section being turned inside out and bent to provide a concave 30 seat portion and a rounded upwardly curved back, the opposite end thereof being bent and curved downwardly to form a leg rest and arms, formed integral at their ends with corresponding sides of the ends of said section, having arcuately 35 shaped intermediate portions disposed above and at the sides of said seat portion.

6. In a swing, a chair shaped member formed from a flexible strip having its intermediate portion and one end bent longitudinally and transversely to provide a concave seat and a rounded upwardly curved back rest, respectively, the opposite end of said strip being bent longitudinally and transversely in the opposite direction and curved downwardly to provide a leg rest, arms 45 connected at their ends to the ends of said strip and having arcuately shaped intermediate portions disposed above and on each side of the seat, and rigid reinforcing members secured across the ends of said strip for fixing the shape thereof. 50

7. An article as in claim 6, and stirrups formed integral with said arms and disposed in depending relationship relatively to the sides of the leg rest.

8. A device as in claim 6, and means for yieldably supporting said chair member from above including hangers secured to the sides of the seat and to the intermediate portions of said arms and projecting upwardly therefrom on either side of the chair shaped member, said hangers reinforcing and fixing the position of said arms relatively to the seat portion. 55

JAMES W. MILLER.
